UNITED STATES PATENT OFFICE.

LEO D. JENSEN, OF CHICAGO, ILLINOIS, ASSIGNOR; BY MESNE ASSIGNMENTS, TO UNITED CHROMIUM, INCORPORATED, OF NEW YORK, N. Y., A CORPORATION OF DELAWARE.

TANK FOR CHROMIUM-PLATING BATHS.

Application filed April 12, 1927. Serial No. 183,024.

This invention relates to tanks for electro-deposition and provides improvements therein.

Chromic acid solutions containing acid radicals are used for the electro-deposition of chromium, and earthenware and lead-lined wooden tanks have been usually used for containing such solutions. Earthenware tanks are somewhat fragile and limited in the sizes which can be obtained. Lead tanks are attacked by the solution and develop perforations in time. Moreover, in metal tanks, or metal-lined tanks, stray currents reach the tanks or tank linings.

15 I have found that a most satisfactory tank can be provided, meeting all physical requirements and capable of being made in any size and capacity desired, by making the tanks of iron or steel and facing these with sheets 20 of glass, or equivalent material not attacked by the solution, and acting as insulators or current-shields between the cathode and the tank-metal. By reason of the high current densities used in chromium plating, and the 25 consequent large currents used in a bath, the saving by cutting down the stray currents, and the advantage of directing all of the current onto the cathode, are of very material consequence. This elimination of stray currents is important not only because of energy 30 efficiency, but particularly because it has a definite effect upon the degree to which articles being plated are covered, and upon the nature and uniformity of the chromium deposit.

An embodiment of the invention is illustrated in the accompanying drawing, of which embodiment—

Figure 1 is a longitudinal sectional view, 40 and

Fig. 2 is a top plan view partially in horizontal section.

Referring to said drawing, numeral 10 designates the metal tank (steel or iron), 45 which is conveniently fabricated of sheets, which may be of suitable size and number to give the size desired and of requisite strength. The sides and ends of the tank are designated by numerals 12, 13, 14 and 15, and the bottom by 16. A rim 20, conveniently of angle iron may be used to strengthen the upper edges of the tank.

Glass sheets are laid on the bottom and against the sides and ends of the tank. Nu-

meral 25 designates the sheet laid on the bottom, 26 the sheets laid against the ends and 27 the sheets laid against the sides. Where the areas to be covered are relatively large, the glass sheets 25, 26, 27 are preferably laid in sections 29, so as to be readily replaced 55 when broken. The sheets also are preferably made of wire-glass, so as not to fall in pieces if broken, as the breaking of a sheet into pieces is not of material consequence as long as the pieces retain their position against the 60 sides and ends of the tank.

Simple fastening means suffice for securing the plates 26, 27 against the sides and ends of the tanks, it only being necessary to hold the sheets against their own weight. Simple 70 means such as strips of metal 32 bent or hooked over the edges or rim of the tank and over the upper edges of the glass sheets are sufficient and are easily removed and replaced in replacing sheets of glass. The solution in 75 the tank serves to oppose any movement of the glass sheets away from the sides and ends of the tank below the fastened upper edges. It is not necessary that joints or seals be provided at the edges of the glass sheets, it having been found that tanks constructed as described show very slight attack on the metal by the solution, so small as to be negligible, and stray currents to the tank are effectively inhibited by the shield constituted by the 80 glass sheets 25, 26, 27.

Tanks constructed as described also lend themselves to heating (or cooling) from without, thus dispensing with coils (usually of lead) in the bath, showing comparatively 90 rapid deterioration and receiving leakage of current from the electrodes. To this end, the tank is conveniently provided with an outside heating (or cooling) means, here shown as a simple gas heater 40 beneath the underside of the tank. A jacket 42 is conveniently formed around the sides and ends of the tank for confining the temperature controlling medium against the sides and ends. This jacket as shown is open, as this is sufficient with the construction shown. A variety of arrangements for effecting the temperature control through the sides, ends and/or bottom of the tank may obviously be chosen. Inside heating (or cooling) means 100 may however be employed if desired.

Another advantage of the present tank is that cathode articles accidentally coming

against (or purposely supported against) the sides or bottom of the tank are protected against the effect of short circuits, which, owing to the high current densities used in chromium plating, and consequent large currents employed, give rise to dangerous short circuits.

The invention may receive other embodiments than that chosen for illustration, and 10 equivalents of the parts and materials mentioned in the claims are included in their scope.

What is claimed is:—

1. A tank for chromium plating baths, of 15 metal, with glass sheets covering the inside metal faces, adapted to cut off stray currents, and to prevent short-circuits between the electrodes and the inside of the metal tank,

and means for holding said sheets in place, said means holding the upper edges of said 20 glass sheets.

2. A tank for chromium plating baths, of metal, with glass sheets covering the inside metal faces, adapted to cut off stray currents, and to prevent short-circuits between the 25 electrodes and the inside of the metal tank, said glass sheets being wire-glass.

3. A tank for chromium plating baths, of metal, with glass sheets covering the inside metal faces, adapted to cut off stray currents, 30 and to prevent short-circuits between the electrodes and the inside of the metal tank, said glass sheets being in sections.

In witness whereof, I have hereunto signed my name.

LEO D. JENSEN.
